His Attorney

UNITED STATES PATENT OFFICE

JOHN O. LEWIS, OF WESLEYVILLE, PENNSYLVANIA, ASSIGNOR TO GENERAL ELECTRIC COMPANY, A CORPORATION OF NEW YORK

LUBRICATING DEVICE

Application filed January 16, 1929. Serial No. 332,868.

My invention relates to oil reserve bearing lubricating devices of the type employing a storage reservoir in which oil is contained below atmospheric pressure above an outlet opening formed in the lower portion thereof, and from which the flow of oil is regulated by arranging an oil sealed outlet or a vent passage to control the admission of air to the reservoir.

10 It has been proposed, heretofore, to provide for filling a reservoir of this kind, by arranging a passage open to the atmosphere and extending into the reservoir to the region of atmospheric pressure therein. When

15 it was desired to fill the reservoir oil was either poured into the upper end of the passage, or supplied thereto under pressure, so that it flowed through the passage and into the reservoir. In order to provide for the

20 escape of air trapped above the oil level in the reservoir vent valves have been provided or a U-shaped tube has been arranged in the reservoir with one end terminating in the upper portion thereof and the other end communicating with the atmosphere.

25 In some instances the U-shaped tube has been arranged with the side which communicates with the atmosphere in the passage, which was usually provided by a tubular member threaded into the reservoir, so that the tubular member and the U-shaped tube could be removed from the reservoir as a unit.

Vent valves were not desirable because attendants were likely to forget to close them 35 which permitted the unrestricted flow of oil from the reservoir and flooded the bearings. This was particularly objectionable if the lubricating device was used on a motor for example, into which the oil would flow from the bearing and injure the winding insulation.

If a U-tube was used in a device of this kind, when the attendant first filled the reservoir the oil overflowing from the U-tube 45 gave him an indication that the reservoir was full. The overflow of oil trapped a small amount of oil in the U-tube so that upon subsequent filling of the reservoir, the attendant would fill for a short time and, upon seeing the trapped oil appear at the end of the

U-tube, would stop the filling operation before the reservoir was full. For this reason, the U-tube was also objectionable because the bearing was likely to run entirely dry before the usual time for refilling. Moreover, 55 the U-tube was difficult to arrange in the filling tube. If the filling tube and U-tube were cast integrally, complicated cores were required, and if the U-tube was made separate from the filling tube and secured therein the 60 construction was expensive to manufacture, because of the separate operations of making the filling tube and the U-tube and then assembling them in the desired relation.

An object of my invention is to provide a 65 filling device of this character which does not require the use of valves, and from which oil will not overflow until the bearing is entirely full so as to avoid giving the attendant a false indication that the reservoir is 70 full. Another object of my invention is to provide a filling passage in a reservoir of this kind and an associated vent passage which can be readily produced, and in which the construction lends itself readily to being 75 cast either in the walls of the reservoir, or separately in a member adapted to be threaded or otherwise secured in the reservoir. I accomplish these objects by providing a reservoir having a filling passage opening to the atmosphere and extending to the region of atmospheric pressure therein, which is adapted to receive a filling tube for closing the same adjacent the lower end thereof and for directing oil thereinto, and a vent passage terminating in the upper portion of the reservoir and communicating with the lower portion of the filling passage.

80 My invention will be more fully set forth in the following description referring to the accompanying drawing, and the features of novelty which characterize my invention will be pointed out with particularity in the claims annexed to and forming a part of this specification.

85 In the drawing Fig. 1 is an end elevation of the end-head of a motor partly broken away having an oil reservoir and an arrangement for filling the same embodying my invention, a portion of the end-head being bro-

ken away to more clearly show the construction; Fig. 2 is a side elevation of a filling nozzle which may be employed in filling the oil reservoir, and Fig. 3 is a fragmentary view of the structure illustrated in Fig. 1 showing the filling nozzle in position for filling the reservoir.

Referring to the drawing, I have shown my invention in connection with the end-head 10 of a motor in which the shaft 11 of the motor is supported by a bearing 12. The bearing is formed with an opening 13 which communicates with a waste pocket 14 having a removable cover 15 provided with a vent opening 16. An oil chamber 17 is formed in the end-head adjacent the waste pocket which communicates therewith by an opening 18 and oil is supplied to this pocket from an air tight reservoir 19 through openings 18 and 20 formed in the waste pocket. Oil is adapted to be retained below atmospheric pressure in this reservoir and is supplied therefrom to the chamber 17 so as to maintain the oil level therein at 21. An opening 22 is also formed in the waste pocket communicating with the upper portion of the chamber 17 so that the pressure of the air in the chamber above the oil level therein is substantially atmospheric, as the waste indicated at 23 is porous enough to permit the flow of air between the opening 22 and the vent hole 16 in the waste pocket cover 15. Oil is fed from the level at 21 in the chamber 17 and the bottom by the capillary action of the waste 23 or other suitable wicking arranged in the waste pocket.

In accordance with my invention, oil is retained in the air-tight reservoir 19 and fed therefrom through the passages 20 and 18 to the waste pocket 14 and chamber 17, so as to maintain the oil level in the latter at 21, by providing a filling passage 24 opening to the atmosphere through the vent opening 25 in a removable cover 26 and extending below the region of atmospheric pressure in the reservoir which is indicated by the oil level at 27. A vent passage 28 is arranged adjacent the passage 24 having one end terminating in the upper end of the reservoir and the other end communicating at 29 with the passage 24 slightly below the oil level 27 therein. The chamber 17, waste pocket 14 and the lower portion of the reservoir 19 are in substantially free communication as the waste or wicking indicated at 23 is not sufficient to obstruct the flow of oil, so that upon any lowering of the level of the oil below that indicated in the waste pocket 14 and chamber 17, will correspondingly lower the level of the oil at 27. As a result when oil is fed by the waste 22 to the bearing so as to lower the oil level below 21 and 27, air will be admitted from the passage 24 to the vent tube 28 which will slightly increase the air pressure above the oil level in the reservoir 19 and thereby cause oil to flow through the

opening 20 to the waste pocket and the oil chamber until a condition of equilibrium is established. This will occur when the oil level at 21 is raised sufficiently to prevent the admission of air at 29 to the vent passage 28. Under this condition the oil level in the vent tube 28 will, as indicated in the drawing, be the same as the oil level in the reservoir 19, as the upper end of the vent tube communicates with the upper portion of the reservoir, and the other end communicates with the reservoir through the lower end of the passage 24.

In filling the reservoir I employ any suitable device for directing oil into the same which loosely fits the passage 24 so as not to obstruct the flow of air from the vent tube 28 therethrough, and which cooperates with the lower end of the passage to close the same. In this particular instance I have illustrated a filling nozzle or tube 30 which is tapered at 31 to fit a reduced tapered portion 32 at the bottom of the passage 24 for closing the same below the opening of the vent tube at 29, and for directing oil into the reservoir.

When the filling nozzle 30 is arranged, as shown in Fig. 3, to fill the reservoir oil flows into the reservoir 19 and the pressure of the air above the level of the oil therein is increased so that the oil in the vent tube 28 is forced into the passage 24. In order to prevent the oil flowing from the vent tube 28 rising above the upper end of the passage 24 and giving the attendant a false indication that the reservoir is full, I make the filling nozzle 30 small enough so that there is clearance space between the nozzle and the side wall of the passage 24 sufficient to accommodate the oil in the vent tube below the top of the passage. To further insure a substantially free flow of the air from the space above the oil level in the reservoir 19 through the vent tube and the space between the filling nozzle 30 and the passage 24, I provide a groove 33 in the side of the nozzle arranged so that when the filling nozzle is placed in the passage, as shown in Fig. 3, the lower end of the groove terminates substantially at the opening 29 of the vent tube and the upper end thereof terminates above the passage 24. By this construction, when the reservoir is being filled air which is trapped above the oil level in the reservoir 19 during the filling operation will be forced therefrom through the vent tube and will bubble through the oil forced into the space between the filling nozzle and the wall of the passage 24 until the oil level in the reservoir 19 rises above the end of the vent tube 28 which communicates with the reservoir. At this time oil will be forced from the reservoir through the vent tube 28, the passage 29 and into the space between the filling nozzle 30 and the passage 24 until the same rises above the upper end of the passage 24, which will give

the attendant an indication that the reservoir is full. It will be observed, however, that the arrangement is such that this indication will not be given until the reservoir is entirely filled.

5 In order to facilitate the manufacture of my improved filling and vent controlling device for the reservoir, I prefer to form the passage 24 and the vent tube 28 in an integral tubular member 34 having a flange 35 which is threaded into the top of the reservoir so as to form an air tight joint therewith and to which the removable cover 26 is hinged at 36.

10 Modifications of the form of my improved lubricating device will occur to those skilled in the art, so that I do not desire my invention to be limited to the particular construction shown and described, and I intend in the appended claims to cover all modifications 15 thereof which do not depart from the spirit and scope of my invention.

20 What I claim as new and desire to secure by Letters Patent of the United States, is:

1. In combination with a bearing, a lubricating device comprising a storage reservoir 25 adapted to contain oil below atmospheric pressure, means for conducting oil from said reservoir to said bearing, said reservoir having a filling passage opening to the atmosphere 30 and extending to the region of atmospheric pressure therein, said reservoir also having a vent passage terminating in the upper portion thereof and communicating with the lower portion of said filling passage, said filling 35 passage being adapted to receive a filling tube for closing the same below said vent passage and for directing oil into said reservoir.

2. In combination with a bearing, a lubricating device comprising a storage reservoir 40 adapted to contain oil below atmospheric pressure, means for conducting oil from said reservoir to said bearing, a tube open to the atmosphere and extending into said reservoir to the region of atmospheric pressure therein, 45 said tube having a vent passage terminating in the upper portion of said reservoir and communicating with the lower portion thereof, said tube being adapted to receive a filling tube for closing the same and for directing oil 50 into said reservoir.

3. In combination with a bearing, a lubricating device comprising a storage reservoir 55 adapted to contain oil below atmospheric pressure, means for conducting oil from said reservoir to said bearing, a tube secured to the wall of said reservoir, said tube being open to the atmosphere above the top wall of 60 said reservoir and extending to the region of atmospheric pressure therein, said tube having a vent passage formed in the side wall thereof terminating in the upper portion of said reservoir and communicating with the lower portion thereof, said tube being of reduced size below said vent passage to receive 65

a filling tube for closing the same and for directing oil into said reservoir.

4. A filling and venting tube for a reservoir adapted to contain oil below atmospheric pressure comprising a filling passage formed at one end to receive a filling nozzle for closing the passage, and a vent passage communicating with the filling passage intermediate the ends thereof and opening at the other end outside of said tube.

70 5. A filling and venting tube for a reservoir adapted to contain oil below atmospheric pressure comprising a filling passage reduced in size at one end to receive a filling nozzle for closing the passage, and a vent passage 80 communicating with the filling passage closely adjacent the reduced portion thereof and opening at the other end outside of said tube.

75 In witness whereof, I have hereunto set 85 my hand this 11th day of January, 1929.

JOHN O. LEWIS.
